UNITED STATES PATENT OFFICE.

JOSEPH A. AMES, OF COLUMBUS, OHIO, ASSIGNOR TO THOMAS W. McGOVERN, OF COLUMBUS, OHIO.

INSOLE.

1,156,026.

Specification of Letters Patent.

Patented Oct. 5, 1915.

Application filed January 15, 1913. Serial No. 742,120.

To all whom it may concern:

Be it known that I, JOSEPH A. AMES, a citizen of the United States, residing at Columbus, in the county of Franklin and State of Ohio, have invented certain new and useful Improvements in Insoles, of which the following is a specification.

My invention deals with the production of shoe insoles in a built up article of manufacture primarily in so far as it relates to the formation of a marginal ridge or inseam lip as an anchorage for the shoe upper and welt.

In such capacity it is possible to employ 15 a pliable tenacious material, as commercial duck cloth, inexpensive and of great durability, resulting in a very flexible finished product with many other advantages over insoles made solely of leather marginally 20 skived and split to provide an upper and welt attaching lip.

While not particularly concerned herein as to the kind of material, or construction of the major portion or body of the insole, 25 it may represent a suitably outlined blank of a single thickness of material or a composite blank of several layers of different kinds of material securely united with or without a veneer finish upon one side, to 30 which the ridge forming material is secured and which latter feature forms the basis of this invention.

Therefore an object of the invention is to provide an insole layer or base member with 35 an inseam ridge secured marginally around said member upon one side thereof comprising a folded tape secured by a marginal line of stitches with its folded edge toward the marginal edge and with said folded edge 40 bent laterally from the stitching to form a continuous marginal flap or lip as an anchorage to which the shoe upper and welt may be secured.

Further objects and features of the invention are more readily apparent from the description of the accompanying drawings, forming a part of this specification, in which like characters of reference denote corresponding parts throughout the several views 50 of which:—

Figure 1 is a view in perspective showing the underside of the insole with the flap or lip element partially broken away, and, Fig. 2 is a partial section on line 2—2, Fig. 1.

It will be noted from the detailed descrip-

tion that the invention is more specifically aimed to the production of an improved insole of Goodyear type. In its manufacture, the use of leather or similar expensive material may be entirely dispensed with, and a 60 cheaper, more tenacious and flexible material substituted, and its manufacture the result of a series of progressive steps which will be followed in describing the insole, perfunctory merely to aid in a clear conception of the invention. Therefore, initially, the various elements are suitably blanked from the different kinds of material to give them the proper outline desired.

In the drawings the body of the insole is 70 shown as of a single thickness of material, although it is within the aspect of the invention to form the same as a composite blank of several layers of the same or different kinds of material, and its upper surface in either instance may represent a finished surface to eliminate the use of a special sock lining in a finished shoe.

The body member 1 marginally is provided 75 with a folded tape secured thereto by stitching and preferably of an adhesively coated duck material. The duck cloth adhesively coated upon the one side being a commercial product. The coated side of the tape is longitudinally folded upon itself to adhesively 80 unite the laps, which forms convenience in stitching the folded tape to the member 1 and the adhesive, an intermediate layer 5, characteristic for its water-proofing properties offers an advantage in such capacity. 85 The folded tape is marginally secured to the member 1, with its folded edge outward, by a double marginal row of stitching 3, 4, and from the outermost row of stitching the folded edge is bent laterally, forming a continuous flap or lip as a marginal anchorage 90 for inseam stitching, in securing the welt and shoe upper thereto. The lip thus formed is of equal thickness in cross section, and pronounced, affording very easy and 95 convenient tracking of the inseam sewing machine, resulting in an even seam, and includes many other advantages in the process of shoe manufacture, over the use of the customary types of insole. It increases the 100 durability and flexibility of the shoe, and comforts the wearer, for the lip readily yields to compressing, due to its normally flat disposition, so that after inseam stitching the lip can be smoothed without injury 110

to the stitching and with no raised portions perceptible in a finished shoe.

Having described my invention, I claim:

5 An insole comprising a body member and a folded tape secured to the margin of said insole by a line of stitches passing through the two thicknesses of said tape, the folded edge of said tape being bent laterally away

from said body member at said line of 10 stitches to form an upstanding marginal lip.

In testimony whereof I affix my signature in presence of two witnesses.

JOSEPH A. AMES.
